UNITED STATES PATENT OFFICE.

CHARLES GILBERT HAWLEY, OF CHICAGO, ILLINOIS, ASSIGNOR, BY MESNE ASSIGNMENTS, TO CENTRIFIX CORPORATION, OF CLEVELAND, OHIO, A CORPORATION OF DELAWARE.

CENTRIFUGAL FIXTURE.

Application filed November 28, 1924. Serial No. 752,720.

To all whom it may concern:

Be it known that I, CHARLES GILBERT HAWLEY, a citizen of the United States, residing at Chicago, Cook County, Illinois, have invented certain new and useful Improvements entitled Centrifugal Fixtures, of which the following is a specification.

In all processes of distillation and evaporation, and throughout the arts of fluid 10 purification and rectification, as by separators, it is both assumed and desired that the fluid evolved or treated shall leave the drum or container in a pure state, free from foreign substances, such as heavier liquids 15 and solids. But as a rule the conditions controlling and modifying the operation in some measure defeat this primary expectation and purpose, and, eventuate in producing or permitting the escape of impure 20 fluids.

The objects of the invention are to perfect such processes of purification and to provide a simple and reliable device or apparatus for the performance of the perfected 25 process. These objects and the specific character of the invention will presently appear in further detail.

The present invention comprises a centrifugal fixture; that is, a device which does 30 not itself move or rotate, but nevertheless reliably induces a strong centrifugal action within the escaping or discharged fluid, whereby the foreign substances are separated and got rid of. Further the invention comprehends a centrifugal fixture from 35 which the accumulations of foreign substances are certainly and definitely removed from the flowing or escaping fluid in two directions and one or both accumulations are 40 turned to the container or one such accumulation may be discharged externally if it be desired to rid the container thereof.

Further and particularly this invention 45 comprises a centrifugal fixture of the construction and performance above described and which is characterized by a movable or adjustable element by which the capacity and performance of the fixture may be adjusted or governed to suit various or desired 50 conditions of operation.

The invention and further of its details will be readily understood on reference to

the drawing that forms part of this specification, in which:—

Fig. 1 is a vertical cross-section of a steam 55 boiler drum or the like, equipped with an adjustable or regulable centrifugal fixture embodying this invention. Fig. 2 is a plan or end view of the fixture partly in section on the line 2— of Fig. 1 and partly 60 on the line —2^a thereof. Fig. 3 is a longitudinal section of a tuyère ring and its adjustable bottom in a modified form, and Fig. 4 is an end view taken from Fig. 3, partly 65 in section on the line —4 of Fig. 3.

Referring to Fig. 1, 1 represents the pressure drum, 2 the liquid level therein, 3 the outlet opening and 4 the nozzle proper. It will be understood that the offtake pipe joins 70 the nozzle. The end of the drum contains 75 the usual manhole with its cover plate (not shown). But for the presence of the novel apparatus comprising this invention, the fluid or vapor leaving the steam or other space 5 would pass directly to the nozzle 75 4. Instead, this novel apparatus, though composed of parts all of which are stationary, that is non-rotative, subjects the escaping fluid to a rapid whirling action. In consequence of this rapid whirling action 80 substances heavier than the fluid are effectively separated therefrom before the fluid leaves the outlet.

In its best form the apparatus comprises 85 two main portions, to wit, the top member 6 and the bottom member 7. The upper part of the member 7 fits into the bottom of the member 6 and most conveniently the parts are fixedly, though separably, attached one to the other as by means of a plurality of 90 bolts 8 and pressure clips 9. It may be at once explained that as the parts must needs be introduced through the manhole of the drum they must be of a size to permit such introduction. The device as a whole primarily takes its size from that of the outlet 95 3 to be served. Manholes are of standard size. The smaller sizes of this apparatus may be introduced intact, but the larger sizes must be made in separate parts, and devices of the largest sizes, though rarely requiring top members 6 which are made in two parts, usually are fitted with lower parts, i. e. tuyère rings 7 which, for con-

venience of introduction, are made in two parts.

The top member 6 is of generally circular form and is hollow. It is preferably a metal casting, so that all its portions may be integral; thus it is provided with the ears 8' for the bolts 8; with the upstanding portion 6^a; with the tangential nozzle portion 6^b, and with the oppositely extending supporting arms or brackets 6^c. The latter contains slotted openings 6^d and receive the bolts 10 by which the member 6 is bolted to or against the top of the drum 1.

It will now be apparent that the member 6 is essentially a hollow ring. The upstanding part 6^a is a collar, which is larger than the outlet 3 of the drum. Its top is shaped to fit against the top of the drum and make a tight joint therewith. In lieu of a joint at this point the joint may be established between the top of the member 6 and the nozzle 4, as by means of a short nipple or sleeve (not shown). In such case the nipple is held in the top of the member 6 and obviously is pushed up into the nozzle 4 by the pressure of the supporting bolts 10. When the nipple is used the collar 6^a need not be used.

In the top of the hollow ring proper is the central opening 6^e. In its bottom is the larger central opening 6^f. Between the two is the still larger annular cavity or centrifugal race 6^g, the bottom 6^h of which is beveled or coned to merge with the margin 35 of the large opening 6^f. The portion 6ⁱ, forming the top of the cavity 6^g, surrounding the outlet opening 6^e, markedly overhangs the larger opening 6^f. A slight inclination downward toward the center may 40 or may not be given the annular top surface 6ⁱ. Within the portion 6^b is the tangential discharge nozzle 6^j, the walls of which intersect the periphery of the race 6^g, and tangentially merge therewith. A pipe nipple 6^k in the part 6^b completes the top member 6. The annular bottom surface 6^l of the member 6 contains a seat or centering sink, which conveniently receives the top of the lower member or tuyère 7.

50 A discharge pipe 12 leads downwardly from the nipple 6^k. This pipe may terminate with an open end near the bottom of the drum, but preferably leads out through the end of the drum and is connected with an automatic discharge trap. The function of the pipe will be explained hereafter in connection with the operation of the complete apparatus.

60 This present invention, which embraces various like structures by which the defined purposes may be attained, comprehends the employment of tuyères, i. e. rotation inducing members, of differing constructions but all generally typified by the member 7 here- 65 in illustrated. Said member 7 proper as

here shown is made up of a top ring 7^a, a plurality of angular or tangentially positioned tuyère blades 7^b and a bottom ring 7^c. The inner edges of the blades substantially conform to or meet an imaginary cylinder, incidentally indicated by the circle 7^d of Fig. 2. This is true also of the inner periphery of the top ring 7^a, which also is substantially of a size with the large opening 6^f in the bottom of the race member 6. 75 Tuyère blades of either the overlapping arrangement of Fig. 2 or the non-lapping arrangement of Fig. 4 may be used. Being preferably truly tangential to the aforesaid imaginary cylinder, both present tangential 80 impact surfaces to the incoming fluid. The arrangement of Fig. 2 possesses the advantage of both forming and directing the entering streams upon the tangential impact surfaces. A common advantage flows from 85 the fact that the blades form long and relatively thin slots or tuyère openings 7^x and hence, collectively, subdivide the fluid into many thin streams that substantially parallel the axis of the tuyère ring. 90

The bottom ring 7^c of the multiply tuyère member 7, as shown in Figs. 1 and 2, contains a spider 7e having a central hub 7^f. The hub is bored to receive a stem 7^g. Preferably both are threaded so that 95 the stem can readily be adjusted tangentially on the hub of the tuyère bottom. The upper or inner end of the stem carries the bottom proper 7^h of the tuyère ring. This bottom proper may be circular, as well 100 shown in Figs. 1 and 2, or may be of a ratchet like formation as illustrated at 7ⁱ in Figs. 3 and 4. The former is preferable for reasons about to be set forth. But in either case, the movable bottom by its position determines the effective height or 105 length of the tangential tuyères 7^x. In other words, by adjusting the movable bottom or follower 7^h the aggregate effective area of the many tangential tuyères may be increased or decreased with relation to the fixed area of the top outlet 6e of the member 6. The effect of such adjustment is more or less to modify the velocity with 110 which the fluid enters at the tuyères and whirls within the centrifugal fixture as a whole. Thus it becomes an easy matter to adjust the centrifugal fixture to nicely conform to the highest requirements encountered in the operation of steam boilers, evaporators, concentrators and the like. Further, this feature of my invention has a broad application to centrifugal fixtures of many types or designs suited to the purifying of fluids of various kinds moving in 115 or from drums and conduits of different sorts.

120 It may here be explained that when desired a suitable connection may be employed between the stem 7^g and the exterior of the 125

pipe or drum containing the centrifugal fixture proper.

As illustrated in Figs. 3 and 4, the movable tuyère bottom 7^a may be operated and held by a plurality of jackscrews 7¹, in lieu of the single operating stem illustrated in Fig. 1.

An optional guard or hood may or may not be used to prevent the dashing or splashing of slugs of fluid against the tuyère ring 7. This guard appears in dotted lines 13 in Fig. 1. The guard depends from the top casting. It serves to obviate the difficulties of side splashing and squirrel-caging in the drum, the same surrounding and in large measure defending the open tuyères 7^a of the tuyère ring.

Being of little altitude and being suspended from the top of the drum it is obvious that the bottom of this centrifugal fixture is well removed from the agitated surface of the liquid in the drum. The velocity of the emergence of the fluid at the nozzle varies with the difference of pressure within and without the drum. In practice these velocities are high. Approaching the fixture, the vapor or other fluid impacts its surfaces. Finding exits between the tuyère blades and directed by the outer surfaces thereof the fluid is formed into the described relatively thin streams. These streams obviously enter the operatively cylindrical tuyère ring tangentially and encountering the annular arrangement of blades, combine to set up a very rapid whirling action within the tuyère ring and the top member of the fixture. On entering the tuyère openings the streams of fluid forthwith engage or impact the inner surfaces of the tuyère blades. These surfaces being preferably tangential in position, conform to the normal angle of incidence of globules of liquid or particles carried by the streams of fluid. Due to this favorable position and relation the impact is non-disturbing in its effect upon the progress of such globules and particles and instead of being swept away they are virtually left or retained upon the inner surfaces of the tuyère blades. The accumulation of such impurities is proportionate to the quantity thereof present in the fluid passing through the fixture, and, while the deposit takes on the general whirling action of the body of fluid within the tuyère ring, that very whirling action insures the retention of the accumulated substances at the periphery of the whirling body, that is, on the inner sectional periphery of the tuyère ring.

As will be apparent, the main or general movement of the whirling body within the tuyère ring is axially toward the outlet 6^a, which affords a free passage for the purified fluid. The upward sweeping action results in lifting the deposit of impurities to

the top of the tuyère ring and into the bottom opening of the race member 6. Arriving there, the deposit of impurities is immediately forced outwardly by the strong whirling action of the body of fluid within the fixture, that is, by centrifugal force. In this manner the heavier substances are positively and definitely removed from the main stream of fluid just prior to the escape of the fluid at the outlet. And obviously the heavier substances, whirling at relatively high velocity in the relatively remote race 6^a, are successfully retained in the race against possible removal by the outward sweep of the fluid. Indeed, the very effort of the fluid to escape longitudinally through the opening, irrespective of whirling action, tends to crowd the heavier substances into the remote parts of the immediately adjacent race. Once arrived in the race the heavier substances whirling therein immediately encounter the substantially tangential peripheral discharge opening or nozzle 6¹ and leave the fixture through that avenue. Sufficient force is accumulated by the heavier substances to carry them well into the discharge pipe 12. This, added to the elevation of the fixture, admits of the return of the heavier substances to the undersurface portion of the fluid in the drum. Generally, however, it is preferred to get rid of the foreign substances by discharging them from the drum. Outside the drum an automatic discharge trap should be used to prevent the free escape of fluid from the drum and yet provide for the collection and intermittent discharge of the foreign substances delivered thereto by the pipe 12.

The main preventive action of this typical centrifugal fixture having been described, attention is directed to the excess of slug dump openings or spaces provided at the bottom or closed end of the tuyère member 7. These spaces or openings appear between the several tuyère blades 7^a and the periphery 7¹ of the adjustable bottom or follower 7². Similarly they are found in Figs. 3 and 4. If desired additional openings may be provided near the periphery of the movable bottom or follower. Should the quantity of moisture or other impurities entering the tuyère ring at a given instant be of such weight that the carrier fluid, though moving with great velocity, lacks all of the energy needed to set that mass or quantity into rapid rotation and whirl it upward or forward into the collecting and discharging race, there would be danger of the spreading of the impurities across the bottom of the tuyère ring and a failure to completely rid the carrier fluid thereof due to the impurities being caught in the central uptake vortex necessarily existing at the center of the whirling body of fluid in the tuyère ring. The function of the de-

scribed slug dump opening or openings is to allow the excess moisture or impurities to drain back into the drum or container. This occurs notwithstanding the up-rush or inrush of carrier fluid at the periphery of the movable bottom, 7⁵ or 7¹. Further the opening or openings function even in the absence of such masses of impurities as might momentarily overcome the energy of the whirling streams of carrier fluid. It may be pointed out that the drop of pressure within the tuyère ring as contrasted with the pressure in the surrounding space⁵ is negligible. Further, as should be apparent, these streams entering tangentially into a tuyère chamber (the space defined by the annular series of blades) which is of greater diameter than the outlet 6^a, have a distinct tendency to divide, that is, the upper part of each stream initially tends to not only move circularly within the tuyère, but also tends pronouncedly to move upward. The lower part of each stream, on the other hand, tends to move downward. The proportion tending to move upward is very much greater than that tending to move downward by reason of the large opening at the top of the tuyère structure. Thus, it happens that even in the absence of heavy slugs there is a constant tendency to deliver some portion of the burden of moisture or other impurities upon the bottom or floor of the tuyère structure. Except for the openings at the periphery of that floor such small quantity of impurities might be carried across the floor and to the center thereof and find escape upward along the axis of the fixture.

It should now be apparent that as the race that is closely adjacent the fluid outlet is of ample capacity to dispose of all impurities lifted into the same and as provision is now made to prevent the retention of impurities on the bottom of the fixture, the latter becomes well adapted to the ridding of the fluid of the heavier substances or impurities under all conditions of actual operation.

Figs. 3 and 4 are specially referred to in the matter of the widened top ring 7¹ for the tuyère ring. This feature may be included in any and all of the tuyère rings embodied by this invention. By widening the ring 7¹ toward the center an annular overhanging shoulder or abutment 7^{a2} is formed at the tops of the tuyère blades. Obviously this abutment slightly overhangs the outer periphery of the movable tuyère bottom. The purpose of this overhanging shoulder is to momentarily hold the carrier fluid and contained foreign substances against immediate upward movement into the discharge race. Thereby a longitudinally expulsive force is built up in the annular column thus held on the inner periphery of the tuyère ring, and this progressive effort has the effect of more positively

expelling any accumulation of substances downward or outward at the edges of the movable or adjustable bottom.

The centrifugal fixture above typified actually performs and may be relied upon to perform in most satisfactory manner the objects and purposes set forth in the opening of this specification.

Various modifications of the illustrated structure will readily suggest themselves to those who are skilled in the art and the invention is by no means limited to the specific structures herein shown and described.

Having thus described my invention, I claim as new and desire to secure by Letters Patent:

1. The process of purifying fluids that consists in setting the fluid into motion toward an outlet, causing and localizing the rapid rotation of the fluid adjacent said outlet and about the extended axis thereof, thereby collecting the heavier substances centrifugally and withholding them from said axis, modifying as need be the axial extent of the rotation with relation to the volume of flow through said outlet, permitting a marked lateral expansion of the whirling action immediately adjacent said outlet and thereby laterally removing the collected substances from the region of said outlet, and, completing the state of separation of the said substances at a point laterally removed from said outlet, while permitting the purified fluid to depart through said outlet. 100

2. The process of purifying fluids that consists in setting the fluid into motion toward an outlet causing and localizing the rapid rotation of the fluid adjacent said outlet and about the extended axis thereof, thereby centrifugally withholding the heavier substances from said axis, adjusting the axial extent of the rotation with relation to the flow through said outlet, permitting a quantity of said substances to escape longitudinally in a direction opposite from said outlet, permitting a marked lateral expansion of the whirling action immediately adjacent said outlet and thereby laterally removing the remainder of the heavier substances from the region of said outlet, and, completing the state of separation of the last mentioned substances at a point laterally removed from said outlet, while permitting the purified fluid to depart through said outlet. 110

3. The process of purifying fluids that consists in causing and localizing the rapid rotation of a stream of fluid beneath an outlet prior to the exit of the fluid through said outlet, while permitting a steady upward flow of fluid, thereby simultaneously centrifugally separating heavier substances from the fluid, permitting a portion of said substances to escape at the bottom of the 120

region of rotation, and as to the remainder, permitting a marked lateral expansion of the whirling action immediately below said outlet and thereby laterally removing such remainder of substances from the fluid while permitting the purified fluid to rise through said outlet, discharging the elevated substances at a point laterally remote from said outlet and modifying the axial extent of aforesaid localized rotation with relation to the flow of fluid through said outlet.

4. The process of purifying fluids that consists in setting fluid in motion toward an outlet and causing the coaxial rotation of the fluid adjacent said outlet, permitting a marked lateral expansion of such rotation immediately adjacent said outlet, collecting and discharging the centrifugally separated substances at a point laterally remote from said outlet and from time to time modifying the axial extent of the region of fluid rotation and thereby adjusting the operation to the varying flow of fluid at said outlet.

5. The process of purifying fluids that consists in causing and varying the axial extent of the rapid rotation of the carrier fluid adjacent the fluid outlet, thereby centrifugally separating heavier substances from the carrier fluid, causing the progressive momentary movement of the fluid and substances in a direction axially opposite from said outlet and permitting the discharge of some of the separated substances in that direction, permitting the movement of the remainder of the separated substances toward said outlet, but allowing the quick rotative expansion of the fluid and substances in a plane immediately adjacent said outlet and discharging the latter substances at the periphery of such plane while permitting the purified fluid to escape through said outlet.

6. A centrifugal fluid purifying device comprising a race member having a central fluid outlet and a peripheral discharge opening for separated substances in combination with a coaxial annular tuyère adapted to whirlingly direct the fluid into said race member and said tuyère having an adjustable bottom opposite the central outlet in said race member, as and for the purposes indicated.

7. A centrifugal fluid purifying device comprising a race member having a central fluid outlet and a peripheral discharge opening for separated substances in combination with a coaxial annular tuyère adapted to whirlingly direct the fluid into said race member and said tuyère having an adjustable bottom opposite the central outlet in said race member, and said bottom being adapted to peripherally release some of the heavier substances before they can reach said race.

8. A centrifugal fluid purifying device

comprising a multiply tuyèred ring in combination with a relatively adjustable tuyère ring bottom for said ring whereby to vary the length of the tuyères of said ring substantially as described.

9. A centrifugal fluid purifying device comprising a multiply tuyèred ring in combination with a relatively adjustable tuyère ring bottom for said ring whereby to vary the length of the tuyères of said ring and a receiver for the heavier substances separated within said tuyère ring and means for discharging the heavier substances from said receiver.

10. A centrifugal fluid purifying device comprising an annular receiver in combination with a multiply tuyèred member of smaller diameter adapted to whirlingly direct fluid into said receiver, a suitable central fluid outlet, a smaller discharge opening leading from said receiver for the disposal of the heavier substances delivered thereto by the tuyèred member and means for modifying the aggregate effective area of the tuyèred member.

11. A centrifugal fluid purifying device comprising an annular receiver in combination with a multiply tuyèred member of smaller diameter adapted to whirlingly direct fluid into said receiver, a suitable central fluid outlet, a smaller discharge opening leading from said receiver for the disposal of the heavier substances delivered thereto by the tuyèred member and means for modifying the aggregate effective area of the tuyèred member without modifying the width of the tuyères in said member.

12. A centrifugal liquid purifying device comprising an annular receiver having a peripheral outlet for heavier substances and a central outlet for the lighter components of the fluid, in combination with a substantially cylindrical multiply tuyèred ring adapted to whirlingly and coaxially direct the fluid into said receiver, an adjustable bottom within said ring and said ring having an annular abutment 7° overhanging the periphery of said bottom.

13. The centrifugal fluid purifying device comprising a part containing a small and a large central opening and a larger intermediate race chamber, the latter having a peripheral discharge nozzle, in combination with a multiple tangential tuyère ring, coaxial with said openings and having its end attached to the margin of the large opening in said part, an axially adjustable bottom member closing the other end of said tuyère ring, and, a fluid container enclosing said tuyère ring.

In testimony whereof, I have hereunto set my hand this 24th day of November, A. D. 1924.

CHARLES GILBERT HAWLEY.
